(57) **CLAIM**

The ornamental design for an enteral syringe, substantially as shown and described.

DESCRIPTION

FIG. 1 is a perspective view of an enteral syringe according to the present invention.

FIG. 2 is a top view thereof;

FIG. 3 is a bottom view thereof;

FIG. 4 is a first side view thereof;

FIG. 5 is a second side view thereof;

FIG. 6 is a rear view thereof; and,

FIG. 7 is a front view thereof.

The features shown in broken lines depict environmental subject matter only and form no part of the claimed design.
